UNITED STATES PATENT OFFICE.

CHARLES A. HULTQUIST, OF LOS ANGELES, CALIFORNIA.

FLUID-OPERATED DRILL

Application filed April 21, 1919. Serial No. 291,510.

To all whom it may concern:

Be it known that I, CHARLES A. HULTQUIST, a citizen of the United States, residing at Los Angeles, in the county of Los Angeles and State of California, have invented a new and useful Fluid-Operated Drill, of which the following is a specification.

This invention relates to drills of the type
10 operated by compressed fluid, such as air,
and an object of the invention, in general, is
to provide a drill of this type in which the
compressed fluid reciprocates the plunger
and also effects turning of the drill steel.

15 Another object is to make provision for turning the drill steel constantly while the plunger is reciprocating.

Another object is to make provision for controlling the reciprocation of the plunger alone, or simultaneous reciprocation of the plunger and turning of the drill steel, by operation of a single control member into two different positions.

Other objects and advantages will appear
25 in the subjoined detailed description.

The accompanying drawings illustrate the invention:

Figure 1 is a side elevation of a drill constructed in accordance with the provisions of this invention, a drill steel also being shown.

Fig. 2 is an enlarged elevation mainly in vertical section on line indicated by x^2-x^2 , Fig. 1.

Fig. 3 is an enlarged sectional elevation on line indicated by x^3-x^3 , Fig. 1.

Fig. 4 is an elevation from the right of Fig. 2, the throttle valve chamber, gear housing and a portion of the throttle valve being shown in section for clearness of illustration.

Fig. 5 is a plan view partly in section on line indicated by x^5-x^5 , Fig. 4, a portion of the gear housing being partly broken away to contract the view.

45 Fig. 6 is a fragmentary sectional elevation on line indicated by x^6-x^6 , Fig. 4.

Fig. 7 is a side elevation of the throttle valve.

50 There is provided a cylinder 1 which is closed at its opposite ends by heads 2 and 3. The cylinder 1 is provided with a plunger 4 having a portion 5 of reduced diameter passing through an opening 6 in the head 3, the reduced portion being adapted to strike an anvil 7 which is reciprocatively mounted in the bore 8 of a tubular shaft 9, the plunger

portion 5 being adapted to project into the bore 8 when the plunger is moved away from the head 2. The anvil 7 is adapted to engage the inner end of the drill steel 10 which is provided with a portion 11 of angular cross section to fit the angular bore of a bushing 12 which is screw threaded into or otherwise suitably fastened to the outer end of the shaft 9 so as to rotate with said shaft. The inner portion of the shaft 9 is rotatively seated in a bearing 13 which is connected with the head 3, in this instance said bearing being integral with the head 3. The outer portion of the shaft 9 is journaled in a bearing 14 that has an end wall 15 provided with an opening 16 through which the drill steel 10 extends.

Fixed to the shaft 9 by suitable means, such as a key 17, is a worm gear 18 which is accommodated in a housing 19 that may be formed integral with the bearing 14 as shown in the drawings. The housing 19 fits a rabbet 20 formed in the outer end of the bearing 13. The worm gear 18 meshes with a worm 21 on a shaft 22 which is journaled at its opposite ends and intermediately in bearings 23, 24, 24' of the housing 19. The bearing 23 is closed at its outer end by a plug 25 screw threaded thereinto, there being a thrust bearing or washer 26 between the plug 25 and the adjacent end of the shaft 22. 75 80 85 95

The shaft 22 is provided with a rotor in the form of a spur gear 27 that meshes with a spur gear 28 mounted on a shaft 29. The shaft 29 is journaled at its opposite ends in bearings 30, 31 of the housing 19. The housing 19 encloses the worm 21 and spur gears 27, 28 and, in this instance, is provided with a detachable section 32 which is fixed in place by bolts 33. The gears 27, 28 and housing 19 constitute a motor for driving the worm 21 so as to effect turning of the shaft 9 and consequently produce rotation of the drill steel 10. The motor is operated by compressed fluid admitted through a port 34 of the chamber 35 in which the gears 27, 28 substantially fit. The port 34 is at one side of the line of engagement of the gears 27, 28 with one another so that the fluid admitted through the port 34 will cause the gear 27 to turn in the direction of the arrow *a* in Fig. 3. The port 34 communicates through a duct 36 with a throttle valve chamber 37 formed by the head 2, said duct being partly formed in the housing 19, partly in the bearing 13, partly in the head 3, partly in the

cylinder 1 and partly in the head 2. The exhaust of fluid from the chamber 35 takes place through a port 51.

The throttle valve chamber 37 may be tapered and fitting in said chamber 37 is a tapered throttle valve 38 having ports 39, 40 arranged in different planes longitudinally of the throttle valve. The port 39 may be brought into registration with the duct 36 and the port 40 may be brought into registration with another duct 41 which communicates with a port 42 of a valve chamber 43. The valve chamber 43 is provided with a sliding valve 44 adapted to be reciprocated by the compressed fluid admitted through the port 42. The valve chamber 43 and valve 44 may be of any suitable construction and need not be described in detail herein since their specific constructions do not enter into this invention. The valve shown is of a type well known in the art pertaining to pneumatic drills. The ports 39, 40 are of such sizes and are so arranged peripherally of the throttle valve 38 that when the throttle valve is turned to one position both ducts 36, 41 will be closed, and when the throttle valve is turned to a second position the duct 41 will communicate with the port 40 so as to cause reciprocation of the plunger 4, and when the throttle valve is turned to a third position the duct 41 will communicate with the port 40 and the duct 36 will communicate with the port 39 so as to cause simultaneous reciprocation of the plunger 4 and rotation of the drill steel 10. One end of the valve chamber 37 is closed by a tubular plug 45 screw threaded into said valve chamber and adapted to be connected with the fluid-supply tube or hose. The throttle valve 38 is provided with a stem 46 which projects from the other end of the valve chamber 37 and which is provided with a control member in the form of an arm 47 whereby the throttle valve may be rotated into the three different positions above described for shutting off the compressed fluid from the valve chamber 43, admitting the compressed fluid only to the valve chamber 43, and admitting the compressed fluid to both the valve chamber 43 and motor chamber 35.

The cylinder 1, heads 2 and 3, bearing 13 and housing 19 are held together by suitable means and in the instance shown in the drawings these holding means are constructed as follows: The head 2 is provided with perforated ears 48 to receive bolts 49 which also pass through perforated ears 50 projecting from the housing 19. Thus when the bolts 49 are tightened they cause the head 2 and housing 19 to be drawn toward one another so as to clamp the cylinder 1 and bearing 13 between them.

The invention operates as follows: When the operator desires to produce blows on the

drill steel 10, he will turn the handle 47 to such position as to cause registration of the port 40 and duct 41 so as to admit compressed fluid to the valve chamber 43. The valve 44 will be caused to reciprocate by the admitted fluid in a manner well understood in the art pertaining to fluid operated drills so as to alternatively admit the compressed fluid at opposite ends of the cylinder 1 to drive the piston 4 first in one direction and then in the other so as to deliver a series of blows on the anvil 7 which transmits the blows to the drill steel 10.

When the operator desires to also cause rotation of the drill steel 10, he will turn the handle 47 to the position shown in Figs. 2 and 6 of the drawings so as to cause registration, of not only the port 40 with the duct 41, but also of the port 39 with the duct 36, as clearly shown in Fig. 4, so as to not only admit compressed fluid to the valve chamber 43 to cause reciprocation of the plunger 4, as just described, but to also admit the compressed fluid to the motor chamber 35 to cause rotation of the gear 27 and thereby effect turning of the worm 21, worm gear 18, shaft 9 and bushing 12, the rotation of the bushing in turn causing rotation of the drill steel 10.

From the foregoing it is clear that by simply turning one control member into two different positions the separate operation of the plunger 4 or simultaneous operation of the plunger 4 and bushing 12 may be effected at will.

It is to be noted that the ports 39, 40 overlap peripherally of the valve 38, and that the amount of the overlap is at least as great as the diameters of the ducts 36, 49 so that in one position of the throttle valve the ports 39, 40 are both at maximum degree of opening; and so that, when the throttle valve is turned clockwise in Fig. 6 from said position, the degree of opening of the port 40 will be gradually diminished while the degree of opening of the port 39 continues at maximum; and so that, when the throttle valve is turned counter clockwise in Fig. 6 from said position, the degree of opening of the port 39 will be gradually diminished while the degree of opening of the port 40 continues at maximum. A great advantage of this construction is that by appropriate turning of the single throttle valve the plunger speed may be reduced and drill-rotation speed kept at maximum when drilling in seamy material, and the plunger speed may be kept at maximum and drill-rotation speed decreased when drilling in hard material.

If the operator desires to effect rotation of the drill without producing blows thereon he will turn the handle 47 into a fourth position to cause the port 40 to be closed and the port 39 to be opened.

The invention is not limited in its broader phases to the exact details of construction described above and shown in the drawings, but the invention also includes such changes and modifications as may lie within the spirit and scope of the appended claim.

I claim:

In a drill, the combination of a cylinder, heads closing the opposite ends of the cylinder, one of the heads having an opening, 10 a plunger in the cylinder having a portion of reduced diameter passing through the opening, a bearing formed integral with the head having the opening, a tubular shaft 15 having one end journaled in said bearing, an anvil reciprocatively mounted in the bore of the tubular shaft, the reduced plunger portion projecting into the bore of the shaft when the plunger is moved toward said anvil, a bushing screw threaded into the shaft and having a bore of angular cross section 20 for the reception of a drill steel, a worm gear secured to the shaft, a housing for the worm gear fitting against the bearing, a second shaft journaled in the housing, a worm on the shaft in mesh with the worm gear, a spur gear on the second shaft inside of the housing, 25 a third shaft journaled in the housing,

a spur gear on the third shaft in mesh with the first spur gear, the housing having 30 a port to admit an operating fluid, one of the heads having a throttle valve chamber and there being a duct connecting the port with said chamber, a throttle valve in the chamber having ports, a second valve chamber, 35 and a fluid operated valve in the second valve chamber controlling the flow of operating fluid to and from the cylinder, there being a duct connecting the two valve chambers, the throttle valve ports being positioned 40 so that when the throttle valve is in one position both ducts will be closed and so that when the throttle valve is in a second position the second duct will communicate with one of the valve ports and so that when the throttle 45 valve is in a third position the second duct will communicate with the last mentioned valve port and the first duct will communicate with the other valve port.

Signed at Los Angeles, California, this 50
14th day of April, 1919.

CHARLES A. HULTQUIST.
